UNITED STATES PATENT OFFICE.

CHRIST SEIVERT, OF CALIO, NORTH DAKOTA.

WEAR-COMPENSATING JOURNAL-BOX.

1,112,425.

Specification of Letters Patent. Patented Sept. 29, 1914.

Application filed August 21, 1913. Serial No. 786,002.

To all whom it may concern:

Be it known that I, CHRIST SEIVERT, a citizen of the United States, residing at Calio, in the county of Cavalier and State 5 of North Dakota, have invented certain new and useful Improvements in Wear-Compensating Journal-Boxes, of which the following is a specification.

My invention relates to automatic adjusting wear compensating journal boxes of the type in which a beveled key or block is moved transversely of the box to force one of the pillows or bearing blocks toward the other, thus compensating any wear thereof 15 due to the rotation of the shaft.

The invention resides more particularly in the means for automatically moving, locking and adjusting this compensating block, also to the means for disengaging the 20 locking means and to the means for removing the same when desired. Its objects are to provide means for automatically adjusting and locking said block against reverse movement; to provide easy and quick means 25 for disengaging said locking means in order that the block may be adjusted to its original or any intermediate position; to provide easy means for the removal of said block; to provide easy means for adjusting 30 the tension of the spring which actuates the compensating block, and to strengthen and improve the box, all of which objects, among others, are accomplished by the construction, combination and arrangement of parts 35 as hereinafter more particularly set forth, described and claimed.

In the accompanying drawings; Figure 1 represents a side elevation of a crank-arm journal box with my invention applied thereto; Fig. 2, a cross-section on line 2—2 of Fig. 1; Fig. 3, a section on line 3—3 of Fig. 2, with the locking spring disengaging sleeve slipped on the bolt; and Fig. 4, a section on line 4—4 of Fig. 2.

Referring now in detail to the drawings, A designates the crank arm or piston rod; B its journal box; C, the inner pillow or bearing block; D, the outer bearing block or pillow having its outer edge sloping or 45 inclined, as is usual; and E, the shaft.

All parts so far designated are old and well known and may be of any well known construction.

The compensating key or block 1 moves 50 transversely of the box and has its inner edge inclined at a corresponding angle

reversely to, and coöperating with, the outer edge of block D. This block or key 1 is held by screw-thread engagement on a bolt 13 which passes freely through the end of the box opening, transversely thereto, and which is provided with screw-threads 2 from its lower end for the greater part of its length. Its upper end is squared and provided with slanting, round cornered 65 notches 3, for a purpose hereinafter explained. These notches are provided on all four faces of the squared portion, no two being in the same plane, and have their corners rounded, as stated, so that they 70 really form one continuous thread, thus I call the notches "screw or thread notches."

A strap 4, provided with a hole 5 in its bottom for the passage of the lower end of the bolt 13 passes around the boxing and is 75 drawn tightly down and around it by two tapering squared bolts 6 passing through it from opposite sides and bearing on the upper face of the boxing, being drawn tight by means of their respective nuts. The said 80 strap has two converging extensions 7 rigid therewith and preferably integral, which are similarly united or connected at their outer ends to a collar 8, which surrounds the square end of the bolt 13 as best shown 85 in Fig. 2.

A helical spring 9 is passed over the lower end of bolt 13, a washer is next slipped thereon and a nut 10 is then screwed on the end of said bolt, and this nut may be screwed 90 on or off the bolt 13 as much as desired to regulate the compression of the spring 9, thus regulating the automatic downward movement of the compensating block 1 and the tightness of the bearing.

Four resilient keepers 11, of slightly different lengths, no two being of the same length, are riveted at their upper ends to the extensions 7 and the collar 8. These springs 11 are adapted to engage, one at a 100 time only, the notches 3 on the sides of the bolt 13 and, by reason of the arrangement of the notches and the different lengths of the springs, they will lock the bolt and its block 1 against reverse movement after a 105 very slight movement.

Should the wear on block D be excessive this may be taken up by inserting a thin metal plate 15 between the adjacent edges of blocks 1 and D. To do this however it 110 would be necessary to move block 1 to its extreme uppermost position. This may be

accomplished, for this or any other purpose, by slipping the locking spring releasing square metallic sleeve 12 over the squared part of bolt 13 and over the notches 3, thus 5 disengaging the locking springs 11 therefrom, allowing the bolt 13 and block 1 to be forced upward against the action of the spring 9. This sleeve 12 is provided near its upper end with perforations for the 10 insertion of a nail or the like to facilitate its withdrawal.

Should it be desired to remove the bolt 13 and block 1 for the purpose of inserting a new block or bolt or both, or for any other 15 purpose, this may be accomplished by removing the nut 10 and spring 9, inserting a nail or the like in perforation 14 in the squared upper part of bolt 13 and screwing the latter out, the springs 11 following 20 the notches and riding around their rounded corners the same as a nut. To facilitate this action these notches are slightly inclined.

The operation is obvious from the foregoing.

All parts are to be made of metal or other suitable material.

It is obvious that minor changes and alterations may be made in the construction, 30 combination and arrangement of the various parts of my invention, of which only the preferred form is illustrated and described herein, without avoiding the spirit of my invention, which I desire to cover and fully 35 protect by the following claims.

Having thus described my invention, what I claim as new and desire to secure by Letters Patent is:

1. A journal box, a block working therein, a strap surrounding the said box, means 40 for drawing said strap tightly around said box and a collar carried by said strap, in combination with a bolt screwthreaded in said block and passing freely through said 45 box, strap and collar, said bolt being provided on one end with screw-threads and on the other with screw notches formed of a continuous thread, a plurality of resilient keepers of slightly different lengths carried 50 by said strap and collar and engaging said notches one at a time, a nut and washer turned on the screw-threaded end of said bolt and an actuating spring surrounding said bolt and bearing against said strap and 55 the washer to move said bolt and block transversely of said box to compensate for wear.

2. A journal box, a compensating block working therein and a bolt passing freely 60 through said box, but fixedly connected to said block, said bolt having one end squared and provided with screw-notches formed of a continuous thread, in combination with a

spring acting to pull said bolt and block transversely of said box, resilient keepers 65 of different lengths adapted to engage the notches on said bolt, only one resilient keeper engaging the notches at one time, and supports for said resilient keepers connected to the box.

3. In combination with a journal box a compensating key working therein a bolt having screw-threaded engagement with said key, a spring acting to pull said bolt and key transversely of said box means for adjusting the tension of said spring and resilient means engaging said bolt to prevent the reverse movement of said bolt and key.

4. A journal box, a compensating block working therein and a bolt passing freely 80 through said box, but fixedly connected to said block, said bolt having one end squared and provided with screw-notches formed of a continuous thread, in combination with a spring acting to pull said bolt and block 85 transversely of said box, means engaging said notches to prevent reverse movement of said bolt and supports for said means connected to said box.

5. A journal box, a compensating key working 90 therein and a bolt passing freely through said box, but adjustably connected to said key, said bolt having one end squared and provided with notches, in combination with a spring acting to pull said bolt and block 95 transversely of the box, means engaging said notches to prevent reverse movement of said bolt and supports for the said means connected to said box.

6. In combination with a journal box and 100 a wear compensating block working transversely therein, a bolt provided with notches connected to said block and passing freely through said box, a spring surrounding said bolt, means carried on the end of said bolt 105 for compressing said spring and means cooperating with said notches to prevent motion of said bolt in one direction, while permitting it in the other, the said bolt and compensating block being movable at will 110 with relation to each other.

7. In combination with a journal box and a wear compensating block working transversely therein, a bolt provided with a longitudinal series of notches, screw-threaded in 115 said block and passing freely through said box, manually operated means for moving said bolt lengthwise to adjust said block and means engaging said notches to lock said bolt against reverse movement.

In testimony whereof I affix my signature in presence of two witnesses.

CHRIST SEIVERT.
